UNITED STATES PATENT OFFICE.

JOHN McE. AMES, OF NEW BRIGHTON, NEW YORK, ASSIGNOR TO BEN-JAMIN A. HEGEMAN, JR., OF NORTH PLAINFIELD, NEW JERSEY.

TRANSPORTATION-CAR AND THE LIKE.

No. 806,763.

Specification of Letters Patent.

Patented Dec. 12, 1905.

Application filed May 1, 1905. Serial No. 258,213.

To all whom it may concern:

Be it known that I, JOHN McE. AMES, a citizen of the United States, and a resident of New Brighton, in the county of Richmond 5 and State of New York, have invented certain new and useful Improvements in Transportation-Cars and the Like, of which the following is a specification.

The invention relates to improvements in 10 transportation-cars and the like, and pertains more particularly to novel mechanism for opening, closing, and locking the discharge door or doors located at the bottom of the car compartment or compartments.

15 The invention will be fully understood from the detailed description hereinafter presented, reference being had to the accompanying drawings, in which—

Figure 1 is a longitudinal section through 20 a portion of a hopper-car on the dotted line 1 1 of Fig. 4 and illustrates the door-operating mechanism as securing a hopper-car door in closed position, the dotted lines denoting the position of the door when in its open position. Fig. 2 is an enlarged top view of a 25 crank-frame constituting a portion of the door-operating mechanism. Fig. 3 is a side elevation of same. Fig. 4 is a top view of a portion of the center or draft sills of a hop- 30 per-car with door-operating mechanism embodying my invention supported thereby, the Z-bar at the lower edge of the door being the only part of the latter illustrated. Fig. 35 5 is a vertical transverse section through a portion of a usual car having applied thereto door-operating mechanism embodying my invention. Fig. 6 is a side elevation of a portion of the car and illustrates the means located at the outer side of same for locking 40 the door-operating shaft. Fig. 7 is a view corresponding with Fig. 1, but illustrating a modification of the invention in respect of the crank-frame and door-connecting rod. Fig. 8 is a top view of the crank-frame repre- 45 sented in Fig. 7, and Fig. 9 is a side elevation of same.

In the drawings, 10 designates a portion of the side of a hopper-car of usual construction; 11, the draft or center sills of same; 12, 50 a usual type of hinged discharge door or gate at the lower end of the customary inclined floor-section 14, (denoted by dotted lines in Fig. 1,) and 15 a transverse operating-shaft from which through intermediate mechan-

ism the door or gate may be operated. The 55 shaft 15 extends transversely of the car below the inclined floor-section 14 and is journaled at its inner end in a hanger-bearing 16, secured to one of the center sills 11, while at its outer end said shaft is mounted in a plate 60 17, at the outer side of which the said shaft has a polygonal end carrying a locking-plate 18 and adapted beyond said plate to receive a wrench or other suitable tool for rotating said shaft to effect the opening and closing of 65 the door. The locking-plate 18 is of known form and construction and cooperates with pivoted dogs 19 for locking at its outer end the shaft 15. The novel features of the present invention are thus located at the inner 70 portion of the shaft 15 or between the center sills 11, and these features comprise the crank-frame 20 and coöperating parts. The crank-frame 20 of the form presented in Figs. 1 to 5, inclusive, is illustrated in detail in Figs. 2 and 3, from which it will be seen that the said frame is in the form of a casting and comprises the connected crank-arms 21 22, laterally-projecting hub 23, and laterally-projecting shaft 24, the said arms 80 21 22 in the construction shown in Figs. 2 and 3 being connected by the depressed section or saddle 25. The hub 23 projects in one direction from the lower end of the arm 22, and the shaft 24 projects in the opposite 85 direction from the lower end of the arm 21, and the said hub 23 is formed with a polygonal recess or socket 26 to receive the inner end of the operating-shaft 15, which is likewise polygonal in cross-section, Fig. 1, so that 90 the crank-frame 20 may become rigid therewith or keyed thereto. The portion of the operating-shaft 15 which is within the hanger-bearing 16 is circular in cross-section, and beyond the hanger-bearing 16 the end of 95 the shaft 15 conforms to the walls of the recess or socket 26. The shaft 24 of the crank-frame 20 is journaled at its outer end in a hanger-bearing 27, secured to one of the draft-sills and corresponding and being in 100 line with the bearing 16, secured to the other draft-sill, and thus the crank-frame 20 becomes mounted between the draft-sills 11, being supported at one side upon the inner end of the operating-shaft 15 and at its other 105 side by the integral shaft 24, mounted in the bearing 27. Between the outer ends of the crank-arms 21 22, formed by the frame 20,

is secured upon a pivot-pin 28 the upper end of a connecting-rod 29, whose lower end is secured by a pin 30 to the door or gate 12, this rod 29 in the construction shown in Figs. 1 to 5, inclusive, being a plain straight rod. When the door or gate 12 is in its closed position, the crank-arms 21 22 and rod 29 are in the alined relation illustrated in Fig. 1, with the center line through the crank-pin 28, lower pivot-point 30, and rod 29 below the center of the shaft 15, this relation of the parts serving to lock the door or gate 12 in its closed position and being permitted by the fact that the upper portion of the rod 29 may 10 pass down in between the crank-arms 21 22 to the saddle 25, which is below the lower edges of the crank-arms proper and connects the latter, leaving abundant space for the reception of the upper portion of the rod 29 15 and permitting the latter to descend sufficiently between the crank-arms to carry the center of the crank-pin 28 below a center line through the lower pivot-pin 30 and shaft 15. I desire to claim the crank-frame 20 without 20 regard to whether the connecting-rod 29 is straight or bent; but an advantage of the construction shown in Figs. 1 to 5, inclusive, is that the said rod may be straight, as shown, and at the same time during the closing of 25 the door carry the crank-pin at its upper end below the aforesaid center line through the lower pivot 30 and shaft 15 for locking the gate in its closed position.

In Figs. 7, 8, and 9 I illustrate a modified 30 form of crank-frame and connecting-rod, the said features being numbered 31 32, respectively, and this form of crank-frame 31 comprising crank-arms 33 34, recessed hub 35, integral shaft 36, and connecting-hub 37, between 35 the inner ends of said crank-arms and in line with said hub 35 and shaft 36. The only difference between the crank-frame 31 of Fig. 8 and the corresponding crank-frame 20 of Fig. 2 resides in the fact that in Fig. 8 40 the saddle 25 of Fig. 2 has been omitted and that in lieu thereof I connect the crank-arms by means of the integral hub 37. The presence of the hub 37 in the crank-frame 31 necessitates the formation of an offset or bend 45 38 in the rod 32, so that upon the closing of the door or gate 12 the crank-pin 39 at the upper end of said rod may pass downwardly to a sufficient extent to carry its center below a center line through the lower pivot 40 and operating-shaft 15, this being for the purpose of locking the door 12 in its closed 45 position. The crank-frame 31 of Fig. 8 is supported upon the operating-shaft 15 and between the draft-sills in the manner clearly 50 represented in Fig. 5. The construction of crank-frame 20 shown in Fig. 2 permits of the use of a straight connecting-rod 29, while with the construction of crank-frame 31 shown in Fig. 8 a bend 38 or equivalent 55 construction is required in the rod 32, so that

the upper portion of the latter may pass partly around the obstructing hub-section 37.

When it is desired to open the door or gate 12, the locking-dogs 19 will be released from the plate 18 and the attendant will turn the shaft 15 upwardly and toward the left, looking at Figs. 1 and 6, to lift the upper end of the crank-frame and upper end of the door-connecting rod above the aforesaid center line through the shaft 15 and lower pivot-point of said rod; thereby releasing the door mechanism and permitting the pressure against the door or gate 12 to drive the latter open, whence the door may be pushed to its most open position by the direct leverage of the crank-frame and rod. When it is desired to close the door or gate 12, the attendant will reverse the motion of the operating-shaft 15 or rotate the same upwardly and toward the right, looking at Figs. 1 and 6, until the 80 said door has reached its closed position (shown in Fig. 1) and the upper crank-pin has passed below the aforesaid center line through said shaft and lower pivot, when, due to the relation of the crank-arms, operating-shaft, and connecting-rod, the door will be held in its closed position. The door or gate 12 may be further locked in closed position by the engagement of the dogs 19 with the plate 18, as usual, or by any other 90 suitable means.

I direct attention to the fact that the door 12 extends downwardly both when open and closed and is hinged at and hangs from its upper edge and that the rod 29 and crank-frame 20 extend downwardly on an inclined line substantially along the line of the inclined floor-section 14, the rod 29 forming a direct connection from the crank-frame to the lower edge of the door. The transverse 105 shaft 15 is located directly below the longitudinal car-sills and below the inclined floor-section 14, in which position it is conveniently removed some distance from the door 12, but through the crank-frame 20 and rod 110 29 has a direct connection with the lower edge of the hanging door, whereby a very simple and highly efficient door-operating mechanism is produced.

In the construction presented in this application the crank-frame 20 is an integral frame and substantially spans the space between the center sills 11 and the shaft 15, extends to and engages said frame, but does not cross said space. In my copending application, Serial No. 258,212, filed May 1, 1905, I present a construction in which the operating-shaft extends across the space between the center sills and is offset in line with said space and has crank-arms applied 120 upon it at opposite sides of its offset portion.

What I claim as my invention, and desire to secure by Letters Patent, is—

1. In a car having an inclined floor-section and a downwardly-hanging discharge-door 130

- at the lower end thereof, the door mechanism comprising the crank-frame affording connected crank-arms, hub and shaft mounted between the draft-sills, a bearing for said shaft, the transverse operating-shaft extending below said floor-section and connected with said hub, and the connecting-rod pivotally mounted at its upper end between said crank-arms and at its lower end pivotally connected with the lower edge of the door, said crank-frame and rod when the door is closed standing substantially in line with each other and with said floor-section; substantially as set forth.
- 5 2. In a car having an inclined floor-section and a downwardly-hanging discharge-door at the lower end thereof, the door mechanism comprising the crank-frame affording connected crank-arms, hub and shaft mounted between the draft-sills, a bearing for said shaft, the transverse operating-shaft extending below said floor-section and connected with said hub, and the connecting-rod pivotally mounted at its upper end between said 20 crank-arms and at its lower end pivotally connected with the lower edge of the door, said crank-frame and rod when the door is closed standing substantially in line with each other and with said floor-section, and 25 said parts being arranged to permit the crank-pin to pass beyond the center line of the shaft and lower pivot-point of said rod when the door is closed, for locking the door closed; substantially as set forth.
- 30 3. In a car having an inclined floor-section and a downwardly-hanging discharge-door at the lower end thereof, the door mechanism comprising the crank-frame mounted between the draft-sills and affording the crank-40 arms and section connecting said arms beyond the pivotal center of said frame, the transverse operating-shaft extending below said floor-section and connected with said frame, and the connecting-rod pivotally mounted at its upper end between said crank-arms and at its lower end pivotally connected with the lower edge of the door, said crank-frame and rod when the door is closed standing substantially in line with each other and 45 with said floor-section; substantially as set forth.
- 45 4. In a car having an inclined floor-section and a downwardly-hanging discharge-door at the lower end thereof, the door mechanism comprising the crank-frame mounted between the draft-sills and affording the crank-50
- arms, section connecting said arms beyond the pivotal center of the frame, hub and shaft, a bearing for said shaft, the transverse operating-shaft extending below said floor-section and connected with said hub, and the connecting-rod pivotally mounted at its upper end between said crank-arms and at its lower end pivotally connected with the lower edge of the door, said crank-frame and rod when the door is closed standing substantially in line with each other and with said floor-section; substantially as set forth.
- 55 5. In a car having an inclined floor-section and a downwardly-hanging discharge-door at the lower end thereof, the door mechanism comprising the integral crank-frame mounted between the draft-sills and affording the connected crank-arms, the transverse operating-shaft extending below said floor-section and connected with said frame, and the connecting-rod pivotally mounted at its upper end between said crank-arms and at its lower end pivotally connected with the lower edge of the door, said crank-frame and rod when the door is closed standing substantially in line with each other and with said floor-section; substantially as set forth.
- 60 6. In a car having an inclined floor-section and a downwardly-hanging discharge-door at the lower end thereof, the door mechanism comprising the transverse operating-shaft extending below said floor-section and having a bearing at the side of the car and in a hanger connected with one of the draft-sills and possessing a polygonal inner end, and the crank-frame between said sills affording the connected crank-arms, hub and shaft, said hub being recessed to receive the inner polygonal end of said operating-shaft, and the shaft of said crank-frame being mounted in a hanger-bearing connected with the other one of said sills, combined with the connecting-rod pivotally mounted at its upper end between said crank-arms and at its lower end pivotally connected with the lower edge of the door, said crank-frame and rod when the door is closed standing substantially in line with each other and with said floor-section; substantially as set forth.
- 65 70 75 80 85 90 95 100 105
- Signed at New York city, in the county and State of New York, this 28th day of April, A. D. 1905.
